(57) **CLAIM**

(21) Appl. No.: **29/138,659**

The ornamental design for an icon for a portable computing device screen, substantially as shown and described.

(22) Filed: **Mar. 15, 2001**

DESCRIPTION

(51) **LOC (7) Cl. 14-02**
(52) **U.S. Cl. D14/493**
(58) **Field of Search** D14/485-95; D18/24-33;
D19/6; D20/11; D21/324-33; 345/700-726,
764-866

FIG. 1 is a front view of an icon for a portable computing device screen, the broken line drawing of a portable computing device screen is for illustrative purposes only and forms no part of the claimed design; and,
FIG. 2 is an enlarged front view thereof, the icon is shown separately for clarity of illustration.
